CLAIM

The ornamental design for a sterilization counter for surgical bur kit holder as shown and described.

DESCRIPTION

FIG. 1 is perspective view of a sterilization counter for surgical bur kit holder according to the present invention; FIG. 2 is a front elevation view of the sterilization counter for surgical bur kit holder; FIG. 3 is a left side elevation view of the sterilization counter for surgical bur kit holder; FIG. 4 is a right side elevation view of the sterilization counter for surgical bur kit holder; FIG. 5 is a rear elevation view of the sterilization counter for surgical bur kit holder; FIG. 6 is a top plan view of the sterilization counter for surgical bur kit holder; and, FIG. 7 is a bottom plan view of the sterilization counter for surgical bur kit holder. The broken lines shown in the drawings depict portions of the sterilization counter for surgical bur kit holder that form no part of the claimed design.

1 Claim, 6 Drawing Sheets
